SHOE SOLE PRESSURE DEVICE

Samuel Plawker, Newark, N. J.

Application August 15, 1946, Serial No. 690,691

3 Claims.

(Cl. 12—33)

1

This invention relates to shoe sole pressure applying devices and in particular to one that will apply a constant uniform pressure to the sole of a shoe in cementing operations.

In shoe manufacturing, at the present time, where advantage is being taken of the new plastic cements for securing an outer sole in place on the shoe, the problem of putting the sole under pressure until the plastic adhesive dries or hardens requires that the sole be pressed with an even pressure throughout the area thereof against the inner sole to which it is applied. The inner sole is sewn to the edges of the upper and then the lower or outer sole is cemented to the inner sole so that it closely adheres thereto and provides a waterproof sole structure that has not been obtainable in shoes, the soles of which have been sewn all the way through.

The important object of my invention, therefore is to provide a pressure device into which the shoe to be finally soled can be quickly placed and to provide a device wherein an even pressure will be applied all over the outer surface of the outer sole so that the connecting adhesive will be spread by the pressure to provide an even cementitious joining agent that will effectively bond the soles together without attention on the part of the operator.

Another important object of the invention is to provide a device for applying pressure which can be mounted on a work bench or a wheel so that in quantity production, each device comes to position before the worker who can quickly remove the finished shoe and insert one to be cemented with a minimum of effort and time.

A still further object of the invention is to provide a pressure device in which an elastic sheet is used so that when the shoe is placed thereon and pressure applied, the pliable sheet will automatically conform in shape to the shape of the bottom of the last on which the shoe is held so that not only even cementing will be the result, but the outer sole will be pressed into shape to conform closely to the shape of the last and the application of even constant pressure will cause the outer sole to conform to the proper shape and be bonded by a uniform thickness of cement or plastic adhesive material which when hardened secures the soles together and provides a waterproof structure that will retain its shape under all atmospheric conditions.

With these and other objects in view, the invention comprises certain constructions herein-after described and then particularly pointed out in the claims and a preferred embodiment of my

invention is illustrated in the accompanying drawing, in which:

Figure 1 is a view in side elevation of the pressure applying holder showing several operating positions thereof in outline,

Figure 2 is a view in end elevation of the holder shown in Figure 1 and a part thereof being broken away to show the interior construction,

Figure 3 is an enlarged section on the line 3—3 of Figure 1 showing the conformation of the elastic sheet used in applying pressure to the shoe,

Figure 4 is an enlarged fragmentary longitudinal section showing the conformation of the sheet in lengthwise engagement with the sole of the shoe,

Figure 5 is a view similar to Figure 1 showing another form of the invention,

Figure 6 is a section on the line 6—6 of Figure 5 showing the parts in elevation,

Figure 7 is a side view of a shoe in which another form of last is used,

Figure 8 is a plan view of the last shown in Figure 5,

Figure 9 is a plan view of the last shown in Figure 7,

Figure 10 is a view in cross section through a last and blanket, and

Figure 11 is a view similar to Figure 10 showing the relation of the blanket and the last under pressure.

Referring to the drawing in detail, 10 indicates a shoe having the usual upper 11, to which is secured by sewing 12 an inner sole 13 to which an outer sole 14 is to be attached, by the use of a plastic cement. Inasmuch as the invention is practiced in manufacture or repair of shoes, a last 15 is employed, about the under surface of which the sole structure is shaped and pressure in a downward direction is exerted on the upper ridged edge 16 of the last by a pressure yoke 17. The latter is supported on a cross rod 18 which is mounted for rocking movement between the upper ends of side arms 19. The arms 19 are pivoted as at 20 to slotted guide strips 21, in the slots 22 of which operate the guide pins 23 that project from the opposite sides of a cup 24.

The cup is formed to present on its upper edge an annular flange 25, the shape of which longitudinally of the cup conforms to the arch and sole portions of the shoe. A blanket or sheet 26 of pliable or elastic material, preferably rubber, is secured by rivets or other fasteners 27 to the flange 25 to form a closure at the top of the cup

and a rest upon which the shoe to be placed under pressure is positioned as shown in Figure 1.

The bottom of the cup 24 is shaped internally to provide a central sleeve 28, and spring seats 29 in the corners thereof. The latter receive the upper ends of compression springs 30 which are supported in suitable pockets 31 in the upper surface of a base 32 and in turn, yieldably support the cup 24 in spaced relation with and above said base. The upward movement of the cup 24 under influence of said springs is limited by engagement of pins 23 in the upper ends of the slots 22.

The cup is lowered against the resistance of the springs by a draw rod 33 which is pinned to the sleeve 28 and depends from the under side of the cup to pass through a suitable bore in base 32. Beneath the base, the rod 33 has secured thereto a stop collar 34 which also limits the rising movement of the cup. Operation of the rod 33 may be provided in different ways. Should base 32 be mounted upon a moving member, such as a wheel, the rod 33 can be provided with a cam roller 35 for engagement with a cam 36 to pull the rod 33 downwardly and lower the cup 24. If the base is mounted upon a bench, the rod may be extended as at 37 to be actuated by a foot lever 38.

When the outer surface of the inner sole has been covered with a plastic cement and the outer sole 14 is applied, the shoe is placed in the holder, the cup having first been pulled down as indicated in outline in Figure 1, against the resistance of the springs. The arms 19 are then swung to a position above the last so that the pressure yoke 17 is positioned thereover. The yoke is actuated by a handle 39 to engage the upper edge of the last 15 as the cup is allowed to rise by operation of rod 33. The force exerted by the springs will cause the elastic sheet 26 to engage the bottom of the shoe with pressure to closely conform in shape to the shape of the bottom of the last to cause the outer sole to be shaped to the last and to be evenly cemented at all points in its area to the inner sole which also closely conforms in shape to the bottom of the last. The force constantly and uniformly applied by the springs and transmitted to the sole of the shoe by the sheet or blanket member will cause the latter to engage the outer sole with an even pressure at all points and the pliable nature of the sheet and its elasticity will augment the pressure applied by the springs.

In the foregoing description I have indicated attachment of the sole throughout its area, but this is only employed in the making of heavy ski shoes where stiffness of the sole and waterproofing is essential. My improvement is preferably applied not only to "sole laying" but also to sole cementing where the sole is glued or otherwise secured to the upper about the peripheral edges of each. As shown in Figure 6, the outer sole 40 is cemented at its marginal edge to the inturned edge of the upper 41 to provide the waterproof structure and at the same time retain flexibility of the sole in the uncemented portion thereof.

The bottom contour of the last varies in curvature throughout its area and when a last, for instance, is placed on any taut surface, such as a solid rubber pad, to shape a sole, an initial pressure is necessary to cause the rubber to conform to the shape of the lasted sole. When additional pressure is then applied as in cementing and holding, the pressure on the sole varies in different areas and lateral slippage of the sole,

uneven distribution of the cementing agent and unequal binding pressures, all of which are objectionable. By my novel limp blanket 42, the weight of the last and shoe will cause the blanket to conform to the shape of the sole and last and cementing pressure applied thereafter will be evenly distributed over the entire area of the sole. The use of the machine for "sole laying" is a feature and where cementing is not to be performed, the pressure can be used to shape the sole to the last so that said sole will closely conform to the bottom contour of the last and thus produce a sole shaped to the foot of the wearer.

15. In the form of the invention shown in Figures 5 and 6, the cup 43 is guided by the pins 44 in slotted guide plates 45, the upper edge of one of which is notched as at 46 to detachably retain the side arms 47 in the outline position shown in Figure 5, by a gravity latch pin 55, to permit a shoe being placed in position for work on the cup. In this instance pressure is applied to the entire sole 40 of the shoe 48, in which the last 49 is positioned, by a self-seating bridge piece 50 having end seat extensions 51 for engagement with the heel and vamp portions of a last and shoe respectively, so that pressure can be applied longitudinally of the shoe. The upper edge of the bridge 50 is shaped to provide a yoke locking seat 52 so that locking movement of the yoke 53 may be limited. The yoke is pivoted on a cross bar 54 fixed in the side arms 47 and is released for pivotal action by release of the handle screw 55A. For use in half sole cementing or shaping, a last 60 having a pressure sole part 61 and a pressure bar 62 is used as shown in Figure 7.

The bar 62 is engaged by the yoke 55 to apply pressure as needed. The top shape of the cup 40 may be varied to fit the type of shoe being worked upon. In Figures 10 and 11 the member 63 is indicative of a combined last and shoe to show how the blanket 42, being flexible or pliable, will automatically conform to the shape of the sole and the last to engage the same evenly under pressure in cementing or sole laying operations. The rod 65 may be threaded as at 66 into the bottom of the cup 43 for pulling the latter down against the resistance of the springs.

50. My invention is not to be restricted to the precise details of construction shown since various changes and modifications may be made therein without departing from the scope of the invention or sacrificing the advantages to be derived from its use.

What I claim is:

1. In a shoe sole pressure device, in combination, a hollow cup, a pliable covering across the top of said cup constituting a support for a shoe, a base, springs for yieldably mounting said cup on the base, side arms pivoted to said base and swingable over said shoe, a bridge piece for engaging a lasted shoe at the front and rear portions thereof, a yoke supported in said arms and movable to engage the bridge to apply pressure to the last shoe against the resistance of said springs whereby said covering engages and conforms the sole of the shoe closely to the shape of the last, and latching means for releasably holding the side arms in an inoperative position.

2. In a shoe sole pressure device, in combination, a hollow cup, a pliable covering across the top of said cup and constituting a support for a shoe, a base, springs for yieldably mounting said cup on the base, side arms pivoted to said

base and swingable over said shoe, a bridge piece for engaging a lasted shoe at the front and rear portions thereof, a yoke supported in said arms and movable to engage the bridge to apply pressure to the lasted shoe against the resistance of said springs whereby said covering engages and conforms the sole of the shoe closely to the shape of the last, a rod depending from said cup for pulling the cup down against the resistance of said springs whereby said yoke may be positioned preparatory for bridge engagement when the cup rises.

3. In a shoe sole pressure device as set forth in Claim 1 including slotted plates adjacent said side arms, and projections on the cup for engagement with said slots to guide the cup in vertical movement.

SAMUEL PLAWKER.
